UNITED STATES PATENT OFFICE.

ALBERT W. MITCHELL, OF NEW HAVEN, CONNECTICUT.

CIGAR AND LIKE CUTTER.

Application filed October 21, 1921. Serial No. 509,838.

To all whom it may concern:

Be it known that I, ALBERT W. MITCHELL, a citizen of the United States, and resident of New Haven, in the county of New Haven 5 and State of Connecticut, have invented certain new and useful Improvements in Cigar and like Cutters, of which the following is a specification.

The present invention relates to devices 10 useful for certain purposes, more particularly as a cigar-tip cutter and the invention consists of improvements in the construction, arrangement, and assemblage of the parts which form the completed article. 15 By means of these improvements the cost of production of the article is materially decreased and the reliability and efficiency of the article is materially increased. Furthermore, the improved article is so designed 20 that the devices introduced with the object of increasing the utility of the article when used as a cigar-cutter, co-operate so as to provide convenient and useful means for igniting matches.

25 In accordance with this invention, new and useful improvements have been made over previously known cigar-cutters and these improvements will be hereinafter described with reference to the accompanying 30 drawings, wherein—

Figure 1 is a perspective view showing the article in a closed condition,

Figure 2 is a perspective view showing the article in an open condition,

35 Figure 3 is a side elevation partly in section,

Figure 4 is a longitudinal section taken on line 4—4 of Figure 1,

40 Figure 5 is a cross section taken on line 5—5 of Figure 1, and

Figure 6 illustrates the blank of which the case is composed.

Referring now to said drawings, the blank 1, (see Fig. 6) of which the case member is 45 made, has two sections 2 united together by the intermediate portion 3, and in the operation of cutting out this blank, the holes 4 are punched out, all the corners of the blank are rounded and the indentation 5 is 50 formed in one of the sections. The edges of the blank are flared or turned over to form lips 6 and the blank is then folded along the dotted lines 7 to bring the two sections into a position parallel with each 55 other, leaving an intervening space to form the pocket 8 which is open at the top and

both ends. The case member so formed is then finished, particularly by removing sharpness of all its edges, and plated and polished if desired. 60

The cutting blade 9 is preferably completely finished before assembling and has the pivot hole 10 formed therein and the cutting edge 11 is rounded and sharpened so as to ensure a perfect shearing cut. The 65 heel 12 is provided to act as a stop and the back edge of the blade is knurled or roughened to provide a better grip for the fingers of the operator when closing the blade and effecting the cutting operation. 70 The extended end 13 having eye 14, provides both a lever by means of which the blade is opened and means for securing the article to a chain, for example.

In assembling the two members of the article, the sections or side walls 2 are simply sprung apart sufficiently to permit engagement of the indentation 5 in the pivot hole 10, and it should be noted that the pivoted connection is preferably such that a certain 75 amount of play is allowed whereby, besides the pivoted angular movement, the blade is given longitudinal movement thereby obtaining the best result for the cutting action of the blade. Furthermore, the spring 80 sides of the case bear against the blade and cause the beveled edge 11 to lie close against one side of the case so that the tip of a cigar, for example, inserted through the registering apertures provided by the holes 4, 85 is cleanly cut off when the operation of cutting is effected. The cutting edge being beveled, a better cutting action is obtained if the cigar tip is inserted into the aperture of which the edge thereof meets the cutting edge and to indicate the side of the article having this aperture, the surface thereof is knurled as at 15 and which knurling also serves to present a better gripping 90 surface.

100 In the operation of the improved article, the blade when not in use, lies well within the pocket of the case, with the heel 12 resting on the bottom of the pocket and which bottom is formed by the connecting portion 3. Only the lever end 13 protrudes, and the spring sides bearing on the blade retain the blade in its closed position even though the pivot of the blade is comparatively loose. It is however necessary that the spring pressure of the sides of the case should only be exerted while the cutting 105 110

action is taking place and when the blade is completely closed, therefore the blade is relieved of the spring pressure in the open or partly opened position by flaring or 5 expanding the edges of the pocket and in doing this the lips 6 are formed. The back of the blade lies below the edges of the lips 6 and with the latter forms a channel open at both ends and this channel having 10 the knurled or abrasive surface at the bottom provides a convenient guiding groove in which a match may be ignited.

To open the blade to permit insertion of the cigar-tip, the article is held in one hand, 15 but not so tightly as to pinch the spring sides, and the lever end 13 is moved downwardly, lifting the blade which is subsequently forced down, by the pressure of the finger on the knurled back of the blade as 20 far as possible and because of the loose pivotal connection aforesaid, a forward and receding movement is given to the blade in the opening and closing thereof, and the receding movement in closing the blade ensures a better shearing action than if angular movement about a fixed point alone is depended upon to effect the cutting. In order to retain the blade in its closed position 25 the lever end 13 is utilized to tightly wedge 30 the blade between the spring sides and this also clears the channel which serves as the match striking means.

It will be noted that the end of the casing adjacent to the pivotal point is rounded 35 so as to be substantially concentric with the pivot therefore the lever end of the cutting member may be conveniently operated to bring the said member to the open position which is limited by engagement of said 40 lever end with the end of the bottom or portion 3 of the casing.

Prior to this invention, it has been proposed to construct a cigar-cutter or the like having but one of the following features: 45 (1) A casing composed of a sheet metal piece bent over to form parallel sides between which a cutting member is pivotally mounted and arranged so that when said member is in the closed position, the back 50 thereof projects from the top of the casing to permit opening of said member: (2) A reciprocating member contained within a casing, said member having an edged back and said casing having parallel sides provided with flared edges forming a trough 55 for the back of said member and which member is given a sliding motion to cause an inserted cigar-tip to engage the cutting edge of an opening in the casing: (3) Means 60 for pivotally connecting a cutting member at one end to the cover of a match box, separate means at the other end of said member for connecting the latter to the box and which latter means comprises a pin engaged

by an elongated slot in said member so that when said cover is operated, motion is given to said member under guidance of said pin and slot: (4) Means for pivotally mounting a cutting member between two sections forming a handle open at the front and 70 back, said means comprising pivots consisting of indentations formed in said sections and which sections are held together by means of a screw located adjacent to the pivotal point of said member so as to hold 75 said indentations in position to act as pivots for said member.

The above mentioned features are embodied in the present invention but in each instance the feature is materially improved 80 and these improvements are clearly defined in the following claims.

I claim:—

1. An article of manufacture as described 85 having a casing composed of a one-piece sheet metal blank bent to form side-walls provided with outwardly flaring upper edges and forming a pocket wholly containing a blade member therein when in its closed position, said blade member being 90 pivotally mounted within said casing, a heel on said blade member serving as a stop which engages the bottom of said pocket when the blade member is in its closed position and said blade member having an extended protruding end providing means 95 whereby the opening pivotal movement of said blade is effected and limited.

2. A cigar-cutter having a pivoted cutting member, a receiving casing for said member, said member having a protruding lever end arranged with co-operating means comprising a shoulder on the bottom of said casing to act as means for effecting a limited opening movement of said member 100 and the pivot for said cutting member being composed of an indentation in said casing engaging an elongated hole in said member. 105

3. An article as described having a casing 110 and a blade pivotally mounted therein constructed and arranged to co-operate so as to provide a combined cigar-cutter and match striking device, said blade having an extended lever end and an abrasive surface on the back edge thereof, said casing having spring side walls frictionally engaging said blade when the latter is closed, registering apertures in said side walls to receive the cigar-tip to be operated on, and said side walls having flared or outwardly expanded edges 115 so as to provide a widened guide groove of which said abrasive back edge of the blade forms the bottom when the blade is in its closed position. 120

Signed at New Haven, in the county of 125 New Haven and State of Connecticut, this 18th day of October, A. D. 1921.

ALBERT W. MITCHELL.
